UNITED STATES PATENT OFFICE

RAY DONZE, OF KITTANNING, PENNSYLVANIA

BRACE AND BIT THEREFOR

Application filed August 5, 1926. Serial No. 127,465.

This invention relates to certain improvements in braces and bits therefor and the primary object of the present invention is to so construct the brace and the bit as to prevent the latter from being unintentionally removed when in operation or out of operation.

A further object of the present invention is to so construct the bit and its jaws that the latter is prevented from becoming detached from the head of the brace when the bit is removed, whereby they are always in position to receive the bit.

A further improvement is to construct the bit with an enlarged inner end that engages projections on the jaws that will prevent the bit from being removed from the brace accidentally.

A further improvement of the present invention is to make the outer ends of the jaws of greater dimension than the dimension of the opening in the head of the brace, whereby the jaws are always retained within the brace to receive the said bit.

Further improvements will appear from the following description:

Figure 1 is a side elevation of a brace showing my improvement in the brace and in the bit.

Figure 2 is a horizontal view on the line 2-2 of Figure 1.

Figure 3 is a vertical horizontal sectional view through the end of the bit and the outer ends of the jaws.

Figure 4 is an enlarged side elevation of the inner end of my improved bit.

Figure 5 is a detached perspective view showing the outer end of one of my improved bit jaws.

In the accompanying drawings, 1 is a bit having at its outer end the usual screw-threaded hollow body 2. Placed within the hollow head and the hollow portion of the brace 1 is my improved construction of jaws 3, of which there are two in number, as is usual in braces of this construction.

Each one of these jaws 3 has its outer end 4 enlarged and the inner edge of the enlarged portion 4 is provided with a longitudinal groove 5 having its inner end forming a shoulder 6, and the inner end of the jaw 7

reduced and extending within the brace and the head 2.

My improved bit is constructed to fit in the groove 5 and is also to cooperate with the shoulder 6 for the purpose to be now explained.

Attention is called to the construction of bit shown in Figure 4. This consists in forming an extremity of the bit with enlarged head 9, the head bearing against the shoulder 6 as shown in Figures 1 and 3. The inner extremity 10 of the bit is tapered, and the taper is preferably angular in cross section. Formed on the bit between the head 9 and the bit 8 proper is an enlargement 11 that in cross section is made substantially oval as shown in Figure 2. The edges of this oval portion 11 are preferably tapered to points 12 and these points fit into the grooves 5 of the jaw portions 4.

In Figure 1 it will be observed that the jaws 3 have their enlarged ends 4 of a size which will prevent them from passing through the opening 13 formed in the head and through which opening the bit 8 proper passes when the parts are in operative position. This opening 13 is large enough to permit the enlargements 11 and 9 of the bit to pass through it when being placed in position in the head of the brace.

From the foregoing description and construction as shown, it will be noted that the shoulder 6 at the inner end of the bit will prevent it from being accidentally removed from the brace. For instance in turning the same backward and at the same time pulling outward to remove the bit from a drilled hole, the bit cannot be accidentally removed even should the head become loosened. Attention is also directed to the fact that the oval or substantially diamond shaped portion 11 engaging the grooves 5 will prevent the bit from turning even though the jaws be loose in their engagement with the bit.

Attention is also directed to the fact that when the bit is removed the jaws 3 cannot by accident fall out through the opening 13 since the opening is smaller than the enlarged head of each of the jaws.

The head 2 is substantially of ordinary con-

struction, its inner portion 14 being tapered and adapted to engage the outer edges 15 of the jaws for forcing the latter together and thus clamping the bit in position therein.

5 The foregoing construction can be changed or modified within certain limits without departing from the spirit and scope of my present invention, so long as such change is within a fair interpretation of the appended 10 claims.

Having thus described my invention, what I desire to claim and secure by Letters Patent of the United States is:

1. An improved brace and bit therefor, said 15 bit comprising a stem having adjacent its upper end a portion angular in cross section, the end of the bit above said angular portion terminating in an enlarged head, the brace provided with an adjustable head carrying 20 jaws operatable thereby, said jaws being longitudinally grooved and said grooved portions adapted to engage the angular portion of the bit and lock it against rotation, and the jaws above said grooves being reduced to receive and interlock with the enlarged head of 25 the bit to hold the bit against outward movement from said brace head.

2. An improved brace and bit therefor, said bit provided with a stem having an enlarged portion angular in cross section sur- 30 mounted by an enlarged head having flattened portions at its base and adjacent its lower end, said brace provided with an adjustable head carrying jaws operatable thereby, 35 said jaws being longitudinally grooved and said grooved portions adapted to interlock with the angular portion of the bit to prevent the bit from rotating, and said jaws above said grooves being reduced and provided with 40 L-shaped flattened shoulders adapted to receive and engage the flattened portions of the enlarged bit head to prevent the outward movement of the bit.

In testimony whereof I hereunto affix my 45 signature.

RAY DONZE.
